UNITED STATES PATENT OFFICE.

JOHAN M. ANDERSEN, OF BOSTON, MASSACHUSETTS.

DESIGN FOR A HANGER.

SPECIFICATION forming part of Design No. 23,246, dated May 1, 1894.

Application filed February 23, 1894. Serial No. 501,311. Term of patent 14 years.

To all whom it may concern:

Be it known that I, JOHAN M. ANDERSEN, residing in Boston, in the county of Suffolk and State of Massachusetts, have invented and produced a new and original Design for a Straight-Line Hanger, of which the following description, in connection with the accompanying drawings, is a specification, like letters on the drawings representing like parts.

10 This design relates to a straight line hanger for the trolley wire employed in the overhead system of electric railways, and consists in a straight line hanger distinguished by its peculiar shape, which will be hereinafter set forth and claimed.

15 Figure 1 is a front elevation of a straight line hanger embodying this design, and Fig. 2, is a side elevation looking toward the left in Fig. 1.

20 The leading feature of my design consists in a body portion *a* made in the shape of a frustum of a cone, and arms *a'* *a''* extended substantially horizontally from diametrically opposite sides of the body portion near the

base or bottom of the body *a*, and having 25 downwardly curved fingers *b* *b'* at their ends. The fingers *b* *b'* project toward the front of the body *a* and away from the back or that portion of the body *a* having formed in it the substantially semicircular groove *b'* for the 30 reception of the span or other supporting wire. The arms *a'* *a''* are made substantially wide at the points of juncture with the body *a* as shown in Fig. 2. The frustum-shaped body *a* is provided with a threaded neck *c'* upon 35 which is fitted a cap *c''*. The base of the body *a* is enlarged or thickened as at *c''*.

I claim—

The design for a straight line hanger consisting of the design herein shown and described.

In testimony whereof I have signed my name to this specification in the presence of two subscribing witnesses.

JOHAN M. ANDERSEN.

Witnesses:

JAS. H. CHURCHILL,
J. MURPHY.
